UNITED STATES PATENT OFFICE.

GRANT I. RAWSON, OF DETROIT, MICHIGAN, ASSIGNOR, BY MESNE ASSIGNMENTS, TO DIAMOND POWER SPECIALTY CORPORATION, OF DETROIT, MICHIGAN, A CORPORATION OF MICHIGAN.

BOILER CLEANER.

Application filed March 17, 1921. Serial No. 452,930.

My invention relates to a new and useful improvement in a boiler cleaner, particularly that class of boiler cleaners in which a cleaning fluid is discharged against or in close proximity to the tubes of the boiler for removing the soot and ashes therefrom.

One of the objects of the invention is to provide a boiler cleaner of the class described which may operate from the side of the boiler and which will be adapted to effectively and quickly clean the tubes of the boiler and which will be protected from the heat of the boiler furnace when not in use.

Another object is to provide a boiler cleaner which will operate from the side of the boiler and which is pivotally mounted to provide for the direction of the cleaning fluid toward a specified portion of the boiler tubes.

Another object of the invention is to provide in a boiler cleaner of this class a nozzled member provided with a plurality of nozzles which member may be projected into the boiler setting and withdrawn therefrom automatically.

Other objects will appear hereinafter.

The invention consists in the combination and arrangement of parts hereinafter described and claimed.

The invention will be best understood by reference to the accompanying drawings which form a part of this specification, and in which,

Fig. 1 is a side elevational view of a boiler with some of the parts removed showing the assembly of the invention thereon.

Fig. 2 is a central sectional view of the invention.

Fig. 3 is a fragmentary sectional view of a part of the invention.

Fig. 4 is a top plan view of the invention.

Fig. 5 is a front elevational view of the invention.

In a boiler cleaner operating through the side of the boiler setting it is desirable that the nozzle bearing member be oscillated about an axis in order to direct the jets of the cleaning fluid over a maximum area of the boiler tubes.

In order to make the opening formed in the boiler wall of as small di-

mensions as possible so as to prevent the entry of air into the boiler settings as much as possible, it is necessary that the distance from the nozzle to the axis of pivotal mounting be as short as possible. In order to accomplish this, I have constructed a device in which the pivotal axis is practically in contact with the wall of the boiler.

Another problem in a boiler cleaner of this type, is the difficulty of maintaining the opening in the boiler wall tightly closed so as to prevent infiltration of air into the boiler setting. In my invention, I have reduced the opening in the boiler wall to the least possible practicable opening and have provided means which automatically maintains this opening closed at all times when the device is not used to perform a blowing operation.

The invention as shown in Fig. 1 is applied to a boiler which comprises the walls 9 upon which is positioned a drum 10. Communicating with the drum 10 and projecting into the interior of the boiler setting are water legs 11 and 12 which are connected by the water tubes 13 as will be readily understood. Positioned in a suitable opening formed in the boiler wall is a frame 14 comprising side members 18 connected at the opposite ends by suitable cross members. Connected to the side members 18 intermediate the ends thereof are braces 15 and 15^a. Projecting outwardly from the frame may be flanges which are embedded in the brick of the boiler wall. Mounted in the frame 14 is a casing or fitting 19 having an opening 22 formed in said casing. The pipe 21, which is threaded at one end into opening 22, projects through an opening formed in the frame 14 and is swivelly connected by a suitable coupling 26 to a pipe 25 which communicates by means of the pipe 28 with a suitable source of steam supply such as the steam dome of the boiler with which the device is used, a suitable valve 27 being interposed in the pipe 25 to control the delivery of steam therethrough.

Provided in the casing 19 is a cylinder 23 which communicates with the space 20. A shoulder 24 is provided on the casing 19 which engages in an opening formed in the

cross member 15 so as to hold the casing in its movement and to form one of the pivotal connections about which the casing 19 swings, the other pivotal connection being formed by the coupling 26. A washer 16 is secured to the shoulder 24 by means of a suitable set screw 17 threaded into said shoulder, said washer serving to prevent the withdrawal of said shoulder through the member 15.

Slidable in the cylinder 23 is a pipe 29 to the inner end of which is secured a collar 30 which serves as a sort of a piston. Piston rings 31 are positioned in the member 30 so as to assure a snugness in the cylinder 23 in order to prevent the escape of steam around the member 30. The outer end of the pipe 29 is threaded into a T 33. Into one end of said T 33 is threaded a pipe 34, one end of which is closed. A pipe 34' is threaded into the other end of the T, the outer end of said pipe 34' being similarly closed or sealed in order to prevent the escape of steam therefrom through the end. Each of these pipes 34 and 34' is provided with nozzles 35 which permit the discharge of steam therefrom.

It is seen from the description thus far that the frame 14 may be securely mounted in the boiler wall and that the casing 19 is pivotally mounted thereon. When it is desired to clean the boiler the valve 27 is opened and steam turned into the cylinder thereby thrusting the pipes 34 and 34' which ordinarily are withdrawn into the opening formed in the boiler wall, forwardly into the interior of the boiler setting so as to bring these pipes closer to the tubes to be cleaned. The steam issues from the nozzles 35 and serves to clean the tubes of soot and ashes. By swinging the device upon its pivotal mounting the jets issuing from the nozzles 35 are caused to travel longitudinally over a large area of the boiler tubes. A suitable handle, as shown in Figure 2, may be connected to the casing 19 in order to effect this swinging movement. A suitable cap 32 secured to the casing 19 prevents the complete withdrawal of the pipe 29 therefrom.

The opening formed in the wall of the boiler is closed by the panels 36 and 37 which are secured to the frame 14. A small opening separates the panels 36 and 37. A closure 38 is secured to the pipe 29 and serves to maintain this opening normally closed.

When the blowing operation starts and the pipes 34 and 34' move inwardly the member 38 is carried away from its normal position so that the opening 38' is not closed during a blowing operation.

Rods 39 are secured at one end to the T 33 and project through lugs 40 formed on the casing 19. Positioned upon these rods so as to engage at one end the lugs 40 are spiral springs 41. Nuts 42 serve to maintain

the springs in their assembled relation to the rods. As will be readily apparent when the blowing operation starts and the pipes 34 and 34' move inwardly toward the boiler tubes the springs 41 will be compressed. As soon as the steam is shut off from the blower thereby relieving the thrusting pressure, the spiral springs will retract the nozzle bearing members to their normal position.

It is to be noted that the point of pivotal connection is at the inner end of the casing 19 thereby bringing the axis about which the device swings as close to the boiler as possible.

Having thus described my invention, what I claim as new and desire to secure by Letters Patent is:—

1. In a boiler cleaner, the combination with a reciprocatory blower unit, and a pipe for supplying a cleaning fluid to said unit, of a fitting having one end pivoted to turn about the axis of said pipe and having parallel passages substantially transverse to said axis, and communicating with each other at the end of the fitting remote from said axis, one of said passages being in communication with said supply pipe and the other receiving an intake portion of said reciprocatory unit.

2. In a boiler cleaner, the combination with a reciprocatory blower unit and a pipe for supplying a cleaning fluid to said unit, said unit having an inlet portion substantially transverse to said pipe, of a fitting wherein said inlet portion of the unit is mounted for reciprocation, one end of said fitting having pivotal engagement with said supply pipe, said fitting having a passage leading from its pivotal end to its opposite extremity for delivering the cleaning fluid to said unit in all positions of its reciprocation.

3. In combination with a boiler provided with a wall formed with an opening there-through, a boiler cleaner adapted to clean parts of the boiler comprising a blower member reciprocatory through said boiler wall opening and provided with a discharge nozzle adapted to be projected with the blower member rearwardly with respect to the boiler wall toward the boiler combustion chamber, a fitting in which said blower member is reciprocably mounted, said fitting being provided with a cleaning fluid passage communicating with the blower member, and means stationary with respect to the boiler wall for pivotally mounting the said fitting, the axis of pivoting being substantially perpendicular with the axis of projection of the blower unit.

4. In combination with a boiler provided with a wall formed with an opening there-through, a boiler cleaner adapted to clean parts of the boiler comprising a blower member reciprocatory through said boiler wall opening and provided with a discharge

- nozzle adapted to be projected with the blower member rearwardly with respect to the boiler wall toward the boiler combustion chamber, a fitting in which said blower member is reciprocably mounted, said fitting having a cleaning fluid passage communicating with the blower member, and means stationary with respect to the boiler wall for pivotally mounting the said fitting, the axis of pivoting being substantially perpendicular with the axis of projection of the blower unit, said means including a portion of a cleaning fluid conduit for conducting cleaning fluid from a source of supply to said discharge nozzle. 5. In combination with a boiler provided with a wall formed with an opening therethrough, a boiler cleaner adapted to clean parts of the boiler comprising a blower member reciprocatory through said boiler wall opening and provided with a discharge nozzle adapted to be projected with the blower member rearwardly with respect to the boiler wall toward the boiler combustion chamber, a fitting in which said blower member is reciprocably mounted, said fitting being provided with a cleaning fluid passage communicating with the blower member, and means stationary with respect to the boiler wall for pivotally mounting the said fitting, the axis of pivoting being substantially perpendicular with the axis of projection of the blower unit, and means automatically responsive to shutting off the supply of cleaning fluid to the discharge nozzle for retracting the blower unit so as to position the said discharge nozzle within a portion of the said boiler wall opening. 6. In combination with a boiler provided with a wall formed with an opening therethrough, a boiler cleaner adapted to clean parts of the boiler comprising a blower member reciprocatory through said boiler wall opening and provided with a discharge nozzle adapted to be projected with the blower member rearwardly with respect to the boiler wall toward the boiler combustion chamber, a fitting in which said blower member is reciprocably mounted, said fitting being provided with a cleaning fluid passage communicating with the blower member, and means stationary with respect to the boiler wall for pivotally mounting the said fitting, the axis of pivoting being substantially perpendicular with the axis of projection of the blower unit, substantially parallel with the boiler wall and close adjacent thereto. 7. In combination with a boiler provided with a wall formed with an opening transversely therethrough and a plurality of spaced rows of boiler tubes sloping longitudinally along and adjacent the inner surface of said wall, a boiler cleaner adapted to clean the said boiler tubes comprising a blower member reciprocatory through said boiler wall opening and provided with a cleaning fluid discharge nozzle adapted to be projected with the blower member rearwardly with respect to the boiler wall toward the boiler combustion chamber, a fitting in which said blower member is reciprocably mounted, said fitting being provided with a cleaning fluid passage communicating with the blower member, and means stationary with respect to the boiler wall for pivotally mounting the said fitting, the axis of pivoting being substantially perpendicular with the axis of projection of the blower unit, whereby said blower member may be pivotally moved in its projected position to direct the discharge from the nozzle transversely of the said rows of boiler tubes. 8. In combination with a boiler provided with a wall formed with an opening transversely therethrough and a plurality of spaced rows of boiler tubes sloping longitudinally along and adjacent the inner surface of said wall, a boiler cleaner adapted to clean the said boiler tubes comprising a blower member reciprocatory through said boiler wall opening and provided with a cleaning fluid discharge nozzle adapted to be projected with the blower member rearwardly with respect to the boiler wall toward the boiler combustion chamber, a fitting in which said blower member is reciprocably mounted, said fitting being provided with a cleaning fluid passage communicating with the blower member, and means stationary with respect to the boiler wall for pivotally mounting the said fitting, the axis of pivoting being substantially perpendicular with the axis of projection of the blower unit, whereby said blower member may be pivotally moved in its projected position to direct the discharge from the nozzle transversely of the said rows of boiler tubes. 9. In combination with a boiler provided with a wall formed with an opening transversely therethrough and a plurality of spaced rows of boiler tubes sloping longitudinally along and adjacent the inner surface of said wall, a boiler cleaner adapted to clean the said boiler tubes comprising a blower member reciprocatory through said boiler wall opening and provided with a cleaning fluid discharge nozzle adapted to be projected with the blower member rearwardly with respect to the boiler wall toward the boiler combustion chamber, a fitting in which said blower member is reciprocably mounted, said fitting having a cleaning fluid passage communicating with

the blower member, and means stationary with respect to the boiler wall for pivotally mounting the said fitting, the axis of pivoting being substantially perpendicular with the axis of projection of the blower member, and also substantially perpendicular to the sloping boiler tubes, whereby said blower member may be pivotally moved in its pro-

jected position to direct the discharge from the nozzle transversely of the said rows of 10 boiler tubes.

In testimony whereof, I have signed the foregoing specification at Detroit, county of Wayne, Michigan, this 11th day of March, 1921.

GRANT I. RAWSON.
